MARSHALL B. LLOYD, OF MENOMINEE, MICHIGAN, ASSIGNOR, BY MESNE ASSIGNMENTS, TO HEYWOOD-WAKEFIELD COMPANY, OF BOSTON, MASSACHUSETTS, A CORPORATION OF MASSACHUSETTS.

REED-WEAVING MACHINE.

1,395,964.

Specification of Letters Patent.

Patented Nov. 1, 1921.

Application filed October 9, 1918. Serial No. 257,462.

To all whom it may concern:

Be it known that I, MARSHALL B. LLOYD, a citizen of the United States, and a resident of Menominee, county of Menominee, and 5 State of Michigan, have invented a certain new, useful, and Improved Reed-Weaving Machine, of which the following is a specification.

My invention relates generally to improvements in machines for weaving fabric, 10 of which reed is characteristic, and which is composed of a plurality of spaced members called stakes, upon which long strands called fillers are woven over some of the stakes and 15 under others.

This machine in its general construction and operation is similar to that shown and described in my pending application, Serial 20 No. 171,431, filed May 28th, 1917, but is modified in a number of particulars for the manufacture of an endless or tubular reed fabric in which a portion of the tubular fabric is of smaller diameter than other portions. 25 Cross reference is hereby made to said co-pending application which claims certain of the subject-matter herein broadly disclosed, but not claimed.

The general object of applicant's invention is to produce a reed weaving machine 30 for manufacturing reed fabrics of the above character which shall be simple in construction; compact in form; which shall operate rapidly; which shall produce a fabric of great uniformity and strength and without 35 any substantial waste of material; which shall be operable by unskilled labor; which may be quickly made ready for weaving operation; and which shall be of such form that when the woven fabric is completed 40 thereon it can be quickly and easily removed and the machine made ready for the weaving of another fabric.

A particular object of my invention is to provide a machine for weaving a somewhat 45 conical reed fabric in which one end is curved inwardly, providing a portion of less diameter than portions immediately adjacent thereto.

Other objects of my invention are to pro-

vide a weaving machine which can be constructed at lower cost and which can be maintained in working order with a minimum of attention and expense.

My invention consists generally in the form, construction, arrangement and co-operation of the parts whereby the above named objects, together with others which will appear hereinafter, are attainable, and my invention will be more readily understood by reference to the accompanying 55 drawings which illustrate that form of my invention which I consider to be the best at the present time.

In the said drawings:

Figure 1 is a general view of the machine, 65 partly in elevation and partly in section, showing a portion of the fabric completed;—Fig. 2 is a fragmentary view along the line A—A of Fig. 1, the same being upon an enlarged scale;—Fig. 3 is an enlarged view, 70 partially in elevation and partially in section, showing the upper part of the machine with the fabric limiting portion collapsed to permit removal of the woven fabric;—Fig. 4 is a detail view, partially in elevation and 75 partially in section, showing several of the fabric limiting elements and associated parts, the view being upon the same scale as that of Fig. 3;—Fig. 5 is a detail sectional view, upon an enlarged scale, taken along the line 80 B—B of Fig. 4;—Fig. 6 is a detail view, in section, of a portion of the lower part of the machine showing means for automatically throwing the packing fingers into inoperative position to permit removal of the fabric;—and, Fig. 7 is a view similar to Fig. 6, 85 but illustrating all of the packing elements (shown in the view) in the inoperative position.

As a matter of convenience and in order 90 to simplify the description and understanding of the machine, I shall describe the principal parts under separate headings.

The frame.—The frame is characterized by a base portion, 1, filler strand packing 95 mechanism guide portion, 2, and fabric limiting portion, 3. The base portion, 1, comprises a bottom, 4, and upstanding portions,

5 and 6. The portion, 2, comprises spaced parallel plates, 7 and 8, which are connected and rigidly spaced by a plurality of rods, 9, and concentrically spaced around the lower 5 plate, 7, is a ring, 10, which is supported from the upper plate, 8, by means of a plurality of rods, 11. The rods, 9 and 11, are positioned along radial lines (best shown in Fig. 2) and are secured to the plates in a 10 suitable manner such as, for example, by nuts 12 and 13, which permit of convenient assembling and demounting of the parts. The rods 9 and 11, and their fellows, form 15 guides for the sliding portions of the filler strand packing means. In Fig. 1 only two sets of diametrically opposite rods, 9, and 11, are shown, the other similar rods (which would be seen in this view) being omitted for the sake of clearness and simplicity.

20 *Fabric limiting means.*—The fabric limiting portion of the frame is composed of a ring, 15, mounted upon plate, 8. Pivotaly joined to the ring, 15, are a plurality of links, 16, which at their outer ends, 16', are 25 pivotally united to the lower ends, 17', of members 17. The upper portions of the members 17 are pivotally joined at 17" to the plate 18. In Fig. 1 of the drawing only two oppositely disposed members 17 are 30 shown, the others being omitted for the sake of clearness. I might here state that one member 17 is provided for every stake in the reed fabric and that while they are pivotally mounted to permit collapsing thereof, as will 35 be shown shortly, they nevertheless serve, when the machine is in operation, in the same general manner that the fabric limiting means shown and described in the aforementioned pending application serve. The 40 members 17 are given that shape which is desired in the finished fabric, and it will be understood, serve to limit the inward forming tendency of the fabric. The manner in which the members 17 are collapsed to permit 45 removal of the fabric and distended to form an operative templet, will be described later.

Stake holding and positioning means.—The stake holding and positioning means in 50 this instance is characterized by a circular band, 20, which is affixed to the plate 8 and has a plurality of spaced holes 21 of a size to accommodate the stakes 22 therein. The 55 lower ends of the stakes, it will be understood, are inserted in the holes 21 and the stakes upstand therefrom, at first being in somewhat perpendicular position, but flaring outwardly for the reason that the holes, 21, define a circle of less diameter than the 60 circle defined by the largest portion of the templet or fabric limiting means.

Reasonable care should be taken in positioning and alining the stakes so that during the weaving operation they will not become

bent, kinked or otherwise injured, but in this 65 respect the members 17 follow the construction detailed in the above mentioned application and a detailed description of them is not here given for that reason. Each member, 17, in the machine here disclosed, however, carries at the right hand side, and in 70 spaced relation thereto, an upstanding flat blade-like member, 17^A, the function of which is to prevent the packing finger, 35, of the filler strand packing means from 75 undue lateral or side play. The members 17^A terminate somewhat above the plate 8 as the packing fingers that they guide never descend to plate 8.

The fabric limiting means formed by the 80 many members 17 it will be noted is formed rather abruptly inward at 17^B, the lower portion at 17^C being substantially vertical. The filler strands cannot be depended upon to form the stakes to the shape of the fabric 85 limiting means, particularly when rather abrupt turns or bends are to be followed as is the case in the lower part of the fabric under consideration. To make possible the formation of the fabric desired, I provide 90 means for encompassing the stakes and drawing them positively into a position paralleling the straight lowermost portion, 17^C, and when the stakes are pulled into this 95 position and the filler strand is placed under and over the stakes with the proper tension, the stakes are caused to conform to the outwardly bulging or curving portion, 17^B, as is illustrated in the drawings.

The means for drawing the stakes into 100 place in this instance comprises a winch or ratchet member, 200, having a drum portion, 201, to which one end, 202, of a wire loop, 203, is secured, the wire passing completely around the lower part of the fabric limiting means, and having its other end, 204, secured to a stud, 205, fixed in the frame of the machine. By operating the winch, the wire 105 loop can be contracted, thereby drawing the stakes positively and firmly inward. The inward movement of the wire is guided by means of a groove, 206, formed in the spacer blocks, 207, which are secured between and to the lower ends of the fabric limiting means, 17 and the blade 17^A. Thus, as the 110 wire loop is contracted and its diameter reduced, it is caused to move into the groove, 206, and thereby force the stakes into the desired position. It is not thought necessary to describe the winch in detail since it 115 is of ordinary pawl and ratchet construction.

Stake manipulating and controlling means.—The stake manipulating and controlling means is characterized by a plate, 40, which in this instance is in circular form and of a size substantially co-extensive with the outer portions of the members, 17, in one sense forming a continuation thereof. The 120

plate 40 is removably mounted upon the plate, 18, as by means of dowel pins (see Fig. 1), so that when in position these parts rotate together. In the edge of the plate, 40, I form a groove, 42, in which a portion of the helical spring, 43, is accommodated. The spring, 43, is of such size with relation to the plate 40 as to tend to compress it self on the plate and into the groove, 42.

5 The exact construction and operation of the spring is shown and described in the aforementioned pending application, and since a detailed claim thereto is not made in this application, no detailed description will be 10 here given. The plate 40 is provided with vertical grooves, 47, for the accommodation of the stakes and thereby the upper or free ends of the stakes are held in proper spaced relation. The means here shown for manipulating the stakes is substantially the same 15 as that shown and described in said pending application and comprises a wheel, 50, having teeth-like projections, 51. The wheel, 50, is rotatably mounted by means of a stud, 20 52, upon a member, 53, which is stationary relatively to plate 40. The plate 40 carries spaced studs or pins 54, equal in number to the stakes of the fabric, and the wheel 50 carries a gear member 55 upon its under side 25 with which the pins 54 engage. Thus, as the plate 40 is driven, the teeth 51 of the wheel 50 successively engage alternate stakes moving the upper portions of them away from the plate 40. At this point I arrange a 30 member 60 through the center of which the filler strand 62 passes and by means of which the filler strand is laid over and under the stakes, after which the filler strand is properly packed upon the pre-formed fabric by 35 40 means to be shortly described.

There is a tendency for the stakes at times to spring out of their grooves and I have so far found it desirable to provide a coiled compression spring 70 which encircles the 45 stakes just below the helical stake guiding spring, 43, to prevent any such action.

In order to weave the fabric rapidly and yet keep the speed of the parts within reasonable limits, I have illustrated in the present 50 case means for inserting the filler strand at a plurality of points, and the same re-tensioning and pay-out mechanism described in my aforementioned application may be here used and is shown only generally herein, bearing the reference A.

For the purpose of returning the stakes to their proper position in the event they have sprung therefrom, I prefer to provide in this instance wheels 90. These perform the general 55 functions and are similar in construction to those shown and described in my previously mentioned pending application. They are altered, however, in one detail, of which mention should be made, to-wit:—the

wheel, 90, is carried in a fork, 91, the stem, 65 92, of which telescopically co-acts with a housing, 93, which is carried by brackets, 94, which in turn is adapted for a swinging movement as indicated. Within the housing, 93, I provide a spring, 95, which reacts 70 against the stem, 92, thus holding the wheel 90 constantly against the stakes or fabric, and yet yieldingly, so that if necessary, it can be readily repressed.

Filler strand packing mechanism.—It is 75 important that the filler strand be properly and uniformly packed if the resulting fabric is to be of a character suitable for use on high class articles, and the mechanism shown and described in my co-pending application 80 being well suited to this purpose, I have illustrated same in this application. It is characterized by a weight, 90^a, which is mounted for vertical sliding movement 85 between adjacent rods 9 and 11, and by means of stud shafts, 91^a and 92^a, passing therethrough. The stud shaft, 92^a, is provided with rollers, 93^a and 94^a, to reduce the friction incident to sliding movement. In the lower part of the weight I mount a roller 95 90 which in turn rests upon a cam, 96. The shape of the cam is shown in my previously mentioned pending application. It should be understood, however, that the cam rises and falls upon each side of the machine, the 95 purpose of the cam being to elevate the weight and to permit its proper descent during each half revolution of the machine, or, in other words, to elevate the weight and permit its descent for every filler strand that 100 is inserted. A stud shaft, 91^a, passing through the weight, 90^a, is inwardly and outwardly extended to form end portions, 97^a and 98^a. The end portion, 98^a, is provided with a roller, 98^b, which is new in the present 105 application. In my former application the end portion of this stud merely serves as a handle whereby the weight could be manipulated by hand either to test the packer; to permit release of the fabric; or for such 110 other purposes as were necessary or desirable. In the present instance I have provided means for automatically throwing all of the packing arms and fingers into inoperative position to permit release of the fabric, 115 thus obviating the necessity of manually operating each packing element in the act of releasing the fabric. The operation of this automatic means will be better understood if the operation of the packing finger or member is first given. The inner end, 97^a, of the stud, 91^a, is slotted, and the lower end of the upstanding packer arm, 99, enters therebetween, and is arranged for swinging movement therein by means of the pivot pin 100. 120 I also prefer to form an elongated slot, 101, in the lower end of the packer arm, 99, through which the pin, 100, passes, the arm

125

99 being normally pressed upwardly by means of a spring, 102, which normally maintains the pivot pin, 100, in the lower portion of the elongated slot, 101, the purpose of which will be shortly described.

Upon the upper end of the rod, 99, I mount a finger, 103, which has a nose portion, 104, that is normally projected through the spaces between the fabric limiting members, 17, this position being shown by means of dotted lines in Fig. 1, the full lines showing the inner or inoperative position, being also the position which they occupied when passing the filler strand inserting point.

15 The lower part of member 99, *i.e.*, the dotted position, is broken away. The packing arm is continually pulled radially outward by means of the tension spring, 105, which is attached to and extends between the

20 packer arm and one of the weight studs. The outward movement of the finger is limited by means of a collar, 106, upon the packing arm, 99, which engages the member, 17, as it moves outwardly. This construction

25 not only limits the outward movement of the finger but also forms a guide directing its to and fro movement in the path in which the fabric is to be formed, which in this instance corresponds to the shape of the 30 member, 17; furthermore, this yielding construction of the packer arm permits it readily to follow guides of different forms, as may be necessary for the construction of differently shaped fabrics.

35 The cam, 96, which raises the weights, is stationary with respect to the frame portions 2 and 3, which are given rotation by means of belt 113, pulley 113', shafts 113" and 116, bevel gearing 116', and pinion 117 and gear

40 118. The cam 96 is held against rotation by means of upstanding rods, 120, and these rods may be vertically adjusted to vary the height of the cam, 96, by means of nuts 121, 122, engaging upper and lower surfaces of

45 the base portion, 6. Thus, as the parts 2 and 3 of the machine are rotated, the weights are caused to ride upon the inclined portion of the cam, thereby elevating the packer arm, which follows the guide 17 until

50 rollers 123 upon the upper inner ends thereof engage the throw-out plate 18', at which time further continued elevation of the weight causes the arm to swing inwardly, the inward movement continuing until the

55 annular stop portion 124 is reached, at which time the weight, 90^a, has also reached the highest portion of the cam. The weight rides upon the ridge of the cam for a period sufficient to hold the finger in retracted position

60 until it has passed the filler strand inserting point at which time the weight is permitted to descend, and so soon as it starts on its downward course the packer arm, under the influence of the tension spring 105,

65 is immediately drawn radially outward into

position between the spaced members 17. This action is essentially the same as the action shown and described in my co-pending application to which reference may be made if a better understanding is necessary or desired.

When the finished fabric is to be removed from the machine, it is necessary to disengage the packing fingers from the top of the fabric. This is done by moving them into the full line position shown in Figs. 1 and 3. The mechanism for this purpose will be better understood by reference to Figs. 1, 6 and 7. As before stated, when the weights are upon the crest of the cam, the packing finger or arm is in the innermost position shown in the drawings, and in the normal operation of the machine this is necessary to permit the insertion of the filler strand. As a matter of fact, the crest of the cam is horizontal for a distance sufficient to support a number of weights so that a number of packing fingers adjacent the filler inserting point are held in retracted position; this is for the purpose of providing a time element sufficient to permit the convenient insertion of the filler strand. Normally, the weights after leaving the crest of the cam, start down the incline and the packing finger moves outwardly as before described; when, however, it is desired to retract all of the packing fingers as, for example, for the purpose of removing the fabric, I employ special packing finger retracting mechanism.

This mechanism, as here shown, comprises a track-like annular band, 150, suitably supported upon the frame of the machine by means of the standards, 151, which band or track, it will be understood, entirely

encompasses the machine. The upper surface of the track, 150, is at a height such that the roller, 98^b, of the packing weight, will ride thereon when in its highest position. The track, 150, is provided at each side of the crest of the cam with sections 160 and 161.

The section 160 is pivoted at 162 to swing in a vertical plane, whereas the section 161 is provided with a vertical pivot 163 to permit swinging movement in a horizontal plane. As the weights ascend, the rollers, 98^b, thereon will engage the under side of the member, 160, thus raising it and permitting the rollers to enter upon the section 164, as is well shown in Fig. 6. When

the section 161 is held in its inner position, as by means of the locking member 166, once the rolls, 98^b, enter upon the section, 164, they continue to ride around the track, 150, and, continued rotation of the machine

will eventually bring all of the rollers of all of the weights upon the track 150, at which time all of the packing fingers will be in retracted position. This condition is depicted in Fig. 7. It will be understood that when the parts are in this condition the packing

5 fingers are in the full line or retracted position, shown in Figs. 1 and 3, and the fabric can be removed upwardly as soon as the members, 17, are collapsed to the position shown in Fig. 3. To release the fabric, the plate 40, and all the mechanism carried thereby, is lifted from the plate, 18, by any suitable means (not shown) such, for example, as a block and tackle and elevated 10 to a convenient height, as is shown in Fig. 3. The plate, 18, is provided with an elongated bearing portion, 18", which is mounted for free sliding movement on the vertical shaft, 110. Upstanding from the lower 15 plate, 8, is a similar bearing portion, 8". The bearing member, 18", is provided with a collar, 18", and the lower bearing portion, 8", is provided with a collar, 8", and between these collars I interpose a strong 20 compression spring, 110', the action of which is to tend to press the plate, 18, upwardly, the weight and friction of the parts, however, are such that the spring 110' is not strong enough to overcome same, therefore, 25 I positively grip the plate, 18, (as by means of a hoist not shown) and move it upwardly to the position shown in Fig. 3. The spring holds the parts in this position until positively returned. The upward movement 30 of the plate, 18, through the pivoted construction before described draws the members, 17, inwardly to the position shown in Fig. 3 in which position the fabric can be moved upwardly free of the fabric limiting 35 elements. It can be conveniently freed entirely from the machine by lifting it part way directly vertically and then angling it toward the operator. So soon as the fabric is removed the head plate, 40, and its associated mechanism can be lowered, the weight 40 thereof being sufficient to depress the plate, 18, to its normal operating position which action automatically throws the members, 17, outwardly, the lower portions, 17", therefore, 45 of entering slots, 17", provided therefor in the ring, 20. The machine is then ready for the weaving of another fabric which is accomplished in the manner before described.

To return the packing fingers to the operative 50 position from the inoperative position illustrated in Figs. 3 and 7, the locking lever, 166, is turned clear of the track section 161, and section, 161, is then swung outwardly. When the machine is rotated the various 55 packing weights successively pass down the cam which they are permitted to do because the rollers, 98^b, are no longer supported in elevated position when the section 161 is swung outwardly.

60 *Operation of the machine.*

Having described the various structural features and their cooperative relation, I shall briefly state the operation of producing 65 a completely woven fabric thereon. To

this end stakes of the proper length are inserted one in each hole 21, provided therefor, in the band or member 20. The member 20 holds the proper number of stakes in desired spaced relation. The encircling 70 wire 203 is then contracted to draw the stakes inwardly causing them to conform generally to the abruptly curved lower part of the fabric limiting elements. The upper ends of the stakes are passed under the 75 retaining coil 43, each stake entering its proper groove 47 in plate 40. The filler strands may be then threaded over and under the stakes from the point of entrance to the lower part of the fabric limiting elements 80 along the generally curved line defined by the various packing fingers. Or I find that the machine can be started without threading the filler strand over and under these stakes by simply pulling a sufficient length 85 of filler strand from the source of supply so that when the machine is started, the filler strand will be automatically laid in position and carried by the packers from the point of entrance down to the lowest point. 90 Continued rotation of the machine upon the vertical stationary shaft 110 quickly lays in sufficient filler strands to form the fabric, and when the fabric is formed to proper height, the machine is stopped, the incoming 95 filler strands severed, the plate 40 and its associated mechanism raised, the wheels 90 being first moved into the position shown in dotted lines at the left hand part of Fig. 1 so that the head can be freely raised. It 100 will now be understood that practically all of the fingers of the packers rest upon the completed fabric and in order to release the fabric it is necessary to move the fingers inwardly. The fingers are pressed inwardly 105 as before described. When all the fingers are thus released the fabric limiting elements 17 are moved inwardly to the position shown in Fig. 3, the encompassing member 203 having first been released, so 110 that the fabric can be bodily raised and removed from the machine. I neglected to state that when releasing the fabric from the machine the auxiliary stake retaining spring 70 is first stretched over the stake retaining spring 43 and over the top of the stakes so that when the plate 40 is raised there is nothing to catch in the stakes and cause them to bind and prevent free release of the weaving parts. 115

When the fabric has been removed, the plate 18 is moved inwardly thus restoring the fabric limiting elements to their outer or operative position, the head plate 40 lowered into place at which time the machine is ready for another set of stakes and the weaving of another fabric. 120

Inasmuch as this disclosure will readily suggest to others skilled in the art to which this appertains modified structures, I do not 125 130

wish to be limited to the specific construction shown and described except only as may be necessary by limitation in the hereunto appended claims.

5. I claim:—

1. An apparatus for weaving reed fabric and the like embodying therein fabric templet members swingably mounted for movement to an outer operative position and to an inner inoperative position, means formed to receive and hold stakes in weaving relation thereto, and means for effecting the placement of a filler strand upon the outer side of some stakes and upon the inner side of others whereby a fabric can be formed as a separate unit apart from the fabric templet members.
2. An apparatus for weaving reed fabric and the like embodying therein fabric templet members mounted for radial swinging movement to an outer operative position and to an inner inoperative position, means formed to receive and hold stakes in weaving relation thereto, and means for effecting the placement of a filler strand upon the outer side of some stakes and upon the inner side of others whereby a fabric can be formed as a separate unit apart from the fabric templet members.
3. An apparatus for weaving reed fabric and the like embodying therein spaced frame members, fabric templet members extending between said frame members and being pivotally joined thereto whereby relative movement of the frame members away from each other causes movement of the fabric templet members to inoperative position, means formed to receive and hold stakes in weaving relation to the fabric templet members, and means for effecting the placement of a filler strand upon the outer side of some stakes and upon the inner side of others whereby a fabric can be formed as a separate unit apart from the fabric templet members.
4. An apparatus for weaving reed fabric and the like embodying therein spaced frame members, fabric templet members extending between said frame members and being pivotally joined thereto whereby relative movement of the frame members away from each other causes movement of the fabric templet members to inoperative position, and relative movement of the frame members toward each other causes movement of the fabric limiting elements to operative position, means formed to receive and hold stakes in weaving relation to the fabric templet members, and means for effecting the placement of a filler strand upon the outer side of some stakes and upon the inner side of others whereby a fabric can be formed as a separate unit apart from the fabric templet members.
5. An apparatus for weaving reed fabric

and the like embodying therein spaced frame members, fabric templet members extending between said frame members, pivotal connections directly joining the fabric templet members to one frame member at one end, pivoted links joining the fabric templet members to the other frame member at the other end whereby relative to and fro movement of the frame members causes distention and retraction respectively, of the fabric templet members.

6. An apparatus for weaving reed fabric and the like embodying therein fabric templet members having abruptly bulging contours at one place, means formed to receive and hold stakes in proximate relation to the general extension of the fabric templet members, and means for causing stakes to conform to the abruptly bulging contour of the fabric templet members.

7. An apparatus for weaving reed fabric and the like embodying therein a plurality of fabric templet members having abruptly bulging contours at one place, means formed to receive and hold stakes in proximate relation to the general extension of the fabric templet members, and means for causing stakes to conform to the abruptly bulging contour of the fabric templet members, said means comprising an encompassing band and mechanism for contracting same.

8. An apparatus for weaving reed fabric and the like embodying therein spaced frame members, fabric templet members extending between said spaced frame members, pivotal connections directly joining the fabric templet elements to one frame member at one end, pivoted links joining the fabric templet members to the other member at the other end, and a ring on the last mentioned frame member provided with slots in which the link connected ends of the fabric templet members repose when in operative position.

9. An apparatus for weaving reed fabric and the like embodying therein spaced frame members formed for relative to and fro movement, fabric templet members extending between said frame members and being pivotally united thereto, and means for holding the frame members in their most widely separated positions when they have been so placed.

10. An apparatus for weaving reed fabric and the like embodying therein spaced frame members formed for relative to and fro movement, fabric templet members extending between said frame members, means for holding the frame members in their most widely separated positions when they have been so placed, and means for holding the frame members in their most closely associated positions.

11. An apparatus for weaving reed fabric and the like embodying therein spaced

frame members formed for relative to and fro movement, fabric templet members extending between said frame members, means for holding the frame members in their 5 most widely separated positions when they have been so placed, and means for moving the frame members to and holding them in their most closely associated positions.

12. An apparatus for weaving reed fabric and the like embodying therein spaced frame members formed for relative to and fro movement, a shaft on which said frame members are mounted, a compression spring interposed between said frame members and 15 exerting a force tending to move them apart, and means normally restraining the action of the spring.

13. An apparatus for weaving reed fabric and the like embodying therein spaced 20 templet members formed for relative to and fro movement, a shaft on which said frame members are mounted, a compression spring interposed between said frame members and exerting a force tending to move them 25 apart, and means normally restraining the action of the spring, said means comprising a removable head plate and stake manipulating mechanism.

14. An apparatus for weaving reed fabric and the like embodying therein a plurality 30 of spaced fabric templet members, filler strand packing arms arranged adjacent the space between contiguous fabric templet members, said arms carrying fingers 35 normally projecting through said space and extending beyond the outer portion of the fabric limiting elements, means for retracting the fingers from projected positions to permit same to pass under the 40 filler strand at the feed point, and means for arresting the return movement of the packing arms as they successively leave the filler strand inserting position thereby preventing their normal projection.

15. An apparatus for weaving reed fabric and the like embodying therein a plurality 45 of spaced fabric templet members, a plurality of filler strand packing arms arranged adjacent the spaces between contiguous templet members, each said packing arm having a packing finger at its upper 50 end and a weight at its lower end, means for causing the projection of said fingers through the spaces between the fabric templet members and beyond the outer surface thereof, a cam upon which said weights ride, said cam being formed with reversely inclined portions and an intermediate level 55 portion, and means for arresting the normal outward movement of the packing arms.

16. An apparatus for weaving reed fabric and the like embodying therein a plurality 60 of spaced fabric templet members, a plurality of filler strand packing arms arranged adjacent the spaces between contiguous

fabric templet members each said packing arm having a packing finger at its upper end and a weight at its lower end, means for causing the projection of said finger through the space between the fabric templet members and beyond the outer surface thereof, a cam upon which said weights ride, said cam being formed with reversely inclined portions and an intermediate level portion, means for arresting the normal outward movement of the packing arms, said means comprising a track encircling the machine and formed with a pivoted section adapted to be swung to a position to form a gap in the track and to a position to close the gap 70 as and for the purpose specified.

17. An apparatus for weaving reed fabric and the like embodying therein a plurality of spaced fabric templet members, a plurality of filler strand packing arms arranged 80 adjacent the spaces between contiguous fabric templet members, each said packing arm having a packing finger at its upper end and a weight at its lower end, means for causing the projection of said packing finger 85 through the spaces between the fabric templet members and beyond the outer surface thereof, a cam upon which said weights ride, said cam being formed with reversely inclined portions and an intermediate level 90 portion, means for arresting the normal outward movement of the packing arms, said means comprising a track encircling the machine and formed with a pivoted section adapted to be swung to a position to form a gap in the track and to be swung in a position to close the gap and a lock to hold 95 said section in closed position.

18. An apparatus for weaving reed fabric and the like embodying therein a plurality 100 of spaced fabric templet members, a plurality of filler strand packing arms arranged adjacent the spaces between contiguous fabric templet members, each said packing arm having a packing finger at its upper 105 end and a weight at its lower end, means for causing the projection of said finger through spaces between the fabric templet member and beyond the outer surface thereof, a cam upon which said weights ride, said cam being 110 formed with reversely inclined portions and an intermediate level portion, means for arresting the normal outward movement of the packing arms, said means comprising a track encircling the machine and formed with a vertical pivoted section adapted to swing to a position to close the gap, and with a horizontal pivoted section, as and for the 120 purpose specified.

19. An apparatus for weaving reed fabric 125 and the like embodying therein a plurality of spaced fabric templet members, a plurality of filler strand packing arms arranged adjacent the spaces between contiguous fabric templet members, each said packing arm 130

having a packing finger at its upper end and a weight at its lower end, means for causing the projection of said finger through the spaces between the fabric templet members and beyond the outer surface thereof, a cam upon which said weights ride, said cam being formed with reversely inclined portions and an intermediate level portion, means

for arresting the normal outward movement of the packing arms, said means comprising a track encircling the machine, and said weights being provided with rollers positioned to ride upon said track.

In testimony whereof, I have hereunto set my hand this 30th day of September, 1918.

MARSHALL B. LLOYD.
